[57] CLAIM

The ornamental design for folder with calculator, as shown and described.

DESCRIPTION

FIG. 1 is a front and top perspective view of a folder with calculator showing my new design;

FIG. 2 is a front elevational view thereof, the rear elevational view being a mirror image of that shown;

FIG. 3 is a side elevational view thereof, the opposite side view being a mirror image of that shown;

FIG. 4 is a top plan view thereof;

FIG. 5 is a bottom plan view thereof; and,

FIG. 6 is a perspective view thereof in operational condition, the broken lines are for illustrative purposes only and forms no part of the claimed design.

FIG. 1

FIG. 2

FIG. 3

FIG. 4

FIG. 5

FIG. 6
